UNITED STATES PATENT OFFICE.

KALLMANN GLASS, OF NEW YORK, N. Y.

BATH-TUB.

SPECIFICATION forming part of Letters Patent No. 445,314, dated January 27, 1891.

Application filed September 2, 1889. Serial No. 322,675. (No model.)

To all whom it may concern:

Be it known that I, KALLMANN GLASS, of New York city, New York, have invented an Improved Bath-Tub, of which the following is a specification.

This invention relates to a sectional bath-tub, which when folded down is perfectly water-tight and when folded up is adapted to receive a case containing drawers.

10 The invention consists in the various features of improvement more fully pointed out in the claims.

In the accompanying drawings, Figure 1 is a side elevation of my improved bath-tub, showing it folded down. Fig. 2 is a similar elevation showing it folded up; Fig. 3, an end view thereof. Fig. 4 is an enlarged face view of the clasp; Fig. 5, a section on an enlarged scale on line $x-x$, Fig. 1. Fig. 6 is a vertical longitudinal section of the folded tub with the case of drawers; Fig. 7, a side view of the case of drawers when removed from the tub, and Fig. 8 a perspective view of the case without the drawers.

25 The letters $a a'$ represent the two sections of a bath-tub resting on feet and on a railing, respectively, and connected at their upper edges by hinges b . The contiguous edges of the sections $a a'$ are grooved, Fig. 5, for the 30 reception of a rubber gasket b' .

In order to draw and hold the sections $a a'$ together, so as to compress the gasket and form a water-tight joint, I make use of a clasp on each side of the tub. This clasp consists 35 of a pair of face-plates $c c'$, Fig. 5, one screwed to each section $a a'$. To the plate c' there is connected by links c^2 an eccentric or cam c^3 . The links pass through eyes c^4 on the parts c' and permit the eccentric to be folded back 40 sufficiently to clear a bent-up edge c^5 on plate c . When the bath-tub is to be tightened up for use, the eccentric is brought into engagement with the bent plate c and turned to lay

flush upon said plate, as in Fig. 1. This will draw the section a' toward section a , compress 45 the gasket b' , and form a tight joint. To fold the bath-tub up, the cam is swung back to become disengaged from plate c , Fig. 5, the links c^2 permitting it to be sufficiently raised for that purpose.

When the bath-tub is folded up, as in Figs. 3 and 6, it is utilized for the reception of a case of drawers to constitute a bureau. The case containing the drawers d consists of the upright frame e , carrying the rails e' , that 55 support the drawers and which are connected at their rear ends by uprights e^2 . The rails e' are of different lengths, Figs. 6 and 8, according to the difference in size of the two parts of the tub. The frame e rests upon 50 rigid feet f , while the rear ends of the lowermost pair of rails e' are supported upon hinged feet f' . When the case is slid into the tub, the feet f' are folded up, Fig. 6; but when the case is drawn forward the feet f' are made to 65 assume an upright position, Fig. 7.

What I claim is—

1. The combination, in a bath-tub, of sections $a a'$, grooved on contiguous edges, with the gasket b' within the grooves and with the 70 hinges b at the upper edges of sections $a a'$ and with a clasp upon the sides of such sections, substantially as specified.

2. The combination, in a bath-tub, of sections $a a'$, grooved on contiguous edges, with 75 the gasket b' , plate c' , links c^2 , eccentric c^3 , and with the plate c , having bent edge c^5 , substantially as specified.

3. The combination of a sectional folding bath-tub with frame e , rails e' , uprights e^2 , 80 feet f , and hinged feet f' , substantially as specified.

KALLMANN GLASS.
